UNITED STATES PATENT OFFICE.

ELBERT R. WINSLOW, OF KEARNEY, NEBRASKA.

EGG-TESTER.

1,088,505.

Specification of Letters Patent.

Patented Feb. 24, 1914.

Application filed July 15, 1913. Serial No. 779,171.

To all whom it may concern:

Be it known that I, ELBERT R. WINSLOW, a citizen of the United States, residing at Kearney, in the county of Buffalo and State 5 of Nebraska, have invented certain new and useful Improvements in Egg-Testers, of which the following is a specification, reference being had therein to the accompanying drawing.

10 This invention relates to an egg tester and has for its object the production of a simple and efficient means for testing a number of eggs at the same time.

Another object of this invention is the 15 production of an egg tester which is provided with a simple circuit closing means whereby when the eggs are placed within the tester the weight of the same will close the circuit so as to light the lamps carried 20 thereby for allowing the eggs to be tested.

With these and other objects in view this invention consists of certain novel combinations, constructions and arrangements of parts as will be hereinafter fully described 25 and claimed.

In the accompanying drawings; Figure 1 is a perspective view of the egg tester. Fig. 2 is a central vertical section of the same. Fig. 3 is a central vertical section of the egg 30 tester showing the electric lighting means carried by the tester. Fig. 4 is a central vertical section of a portion of the device shown in Fig. 3, the perforated plate being removed. Fig. 5 is a perspective view of the 35 light reflecting plate. Fig. 6 is a central vertical section of a portion of the device illustrating the circuit closing means. Fig. 7 is a sectional view of a portion of the 40 invention illustrating how the light reflecting dome is attached for supporting the same. Fig. 8 is a bottom plan view of a portion of the light reflecting dome showing the attaching means therefor.

Referring to the accompanying drawing 45 by numerals, 1 indicates the usual supporting legs having the braces 2. A supporting bridge 3 is carried upon the upper portion of the legs 1 and this supporting bridge 3 is provided with a vertically extending flange 4. The light reflecting dome 5 is positioned 50 between the legs 1 and is attached to the supporting bridge 3 by soldering the same thereto, or any other suitable means. This dome 5 is provided with the laterally bent lips 6 which are secured to the bridge 3

whereby the light reflecting dome will be held securely in position.

A perforated plate 7 having a bent portion 8 is positioned over the upper portion of the light reflecting dome 5 so as to rest snugly 60 upon the supporting bridge 3. The plate 7 is provided with the perforations 9 which are formed so as to constitute cup-like members for fixedly supporting the eggs. When this plate has been placed upon the supporting bridge 3 and the eggs placed thereon, the conical hood 10 which is pivotally secured to the strip 11, as indicated at 12, may be swung downwardly. As this hood will rest evenly upon the strip 11 all light from the 70 outer side of the tester will be excluded.

The lamp 13 carried by the lower portion of the dome 5 may be illuminated whereby the light will be reflected upon the eggs carried by the plate 7. The upper portion of 75 the hood 10 is open, as illustrated at 14 so as to allow a person to view the eggs carried by the plate. It may be desired, however, that instead of using the lamp 13 some other means may be carried by the tester which 80 will allow the eggs to be tested. In this event the light reflecting plate 15 having the concave bodies 16 may be placed so as to allow the side portions of the same to rest upon the bridge 3. A number of lamps 17 85 may be placed within the openings 18 formed in the reflecting plate and these lamps may be connected by means of the wires 19 and the battery 20 which is positioned within the lower portion of the light 90 reflecting dome 5. A circuit closing arm 21 is secured to this light reflecting plate by means of the coiled spring 22 which is positioned about the arm 21. As this spring will normally be in a contracted position, the 95 upper end of the arm 21 will extend for considerable distance above the plate, as illustrated in Fig. 4. When the perforated plate 7 is positioned above the light reflecting plate and the eggs are placed on the same, 100 the weight will cause the arm 21 to move downwardly whereby the foot 23 will rest upon the shelf 24 carried by the dome 5. As soon as this foot rests upon this shelf 24 the circuit will be closed through the wires 19 105 whereby the lamps 17 will be illuminated.

From the foregoing description it will be seen that a simple and efficient egg tester has been produced which will allow a number of eggs to be tested at the same time and 110

which is provided with a simple and efficient circuit closing means for allowing the interior of the tester to be illuminated, whereby the eggs may be tested.

Having thus described the invention, what is claimed as new, is:—

1. An egg tester comprising a light reflecting dome, means for supporting said dome, a hood pivotally secured to said dome and adapted to close the upper portion of the same, a light reflecting plate carried by the upper portion of said dome, means carried by said plate for closing a circuit, and a perforated plate positioned above said light reflecting plate adapted to carry a number of eggs for testing the same.
2. An egg tester comprising a light reflecting dome, means for supporting the same, a hood secured to the upper portion of said dome and adapted to close the same, a light reflecting plate carried by the upper portion of said dome, said light reflecting plate being provided with a plurality of concave portions adapted to support a plurality of lamps, a circuit closing arm passing through said light reflecting plate, a spring positioned about said arm and adapted to hold the same so as to extend above said light reflecting plate, a shelf posi-

tioned within said dome, electric means positioned within said dome for forming a circuit, a perforated plate positioned above said light reflecting plate, said perforated plate being adapted to receive a number of eggs for testing the same, and being adapted to bear upon the upper portion of said circuit closing arm for bringing the same into engagement with said shelf for closing the circuit and lighting said lamps.

3. An egg tester comprising a light reflecting dome, means for supporting said dome, a hood pivotally secured to said dome and adapted to close the upper portion of the same, a light reflecting plate carried by the upper portion of said dome, electrical means positioned within said dome for forming a circuit, an arm carried by said plate for automatically closing the circuit, and a perforated plate positioned above said light reflecting plate adapted to carry a number of eggs for testing the same.

In testimony whereof I hereunto affix my signature in presence of two witnesses.

ELBERT R. WINSLOW.
